WATERPROOF MICROPHONE

Roland M. Gogolick, Cambridge, and Richard L. Brown, Arlington, Mass., assignors to the United States of America as represented by the Secretary of the Navy

Application September 18, 1945, Serial No. 617,153

7 Claims. (Cl. 177—386)

1

This invention relates to microphones and improvements in methods of their manufacture and is illustrated herein as embodied in a compact microphone having a coating of insulation bonded directly to its transducer.

There has been a need for a satisfactory hydrophone for field measurements of underwater sound. The usual method of waterproofing a hydrophone impairs its inherent sensitivity and tends to make it directional because of the bulk of the waterproofing and the damping effect of air spaces between the water and the transducer. On the other hand, those hydrophones which are sensitive, are relatively fragile and difficult to construct.

Therefore, it is an object of this invention to provide an inexpensive, easily constructed, and rugged hydrophone which is relatively non-directional and in which the connection between the transducer and water is unbroken by air spaces.

Accordingly this invention provides a microphone in which a layer of waterproof insulation surrounds and directly engages the transducer. The insulation which may be neoprene, or rubber, or other synthetic rubber-like material is applied to the transducer by dipping in a solution thereof, whereby the insulation is bonded to the transducer.

A further feature of this invention resides in the provision of an electrostatic shield embedded in the above mentioned insulation. In accordance with the method aspect of this invention, a microphone of this type is made by applying layers of insulation thereto, between which layers is disposed an electrostatic shield. More specifically after one layer of insulation has been applied, a layer of conducting material, constituting the shield, is painted over the insulation. Then a further layer of insulation is applied by a second dipping. Thus, a coating is produced which is firmly bonded to the microphone, and the coating acts as a diaphragm attached directly to the transducer with no air spaces between the transducer and the waterproof coating.

The invention is described with reference to the use of a transducer including Rochelle salt piezo-electric crystals, but other types of transducers may be utilized without departing from the spirit of this invention.

With the above and other objects and features in view, the invention will now be described with reference to the accompanying drawings which illustrate a preferred embodiment of the invention and will be pointed out in the claims.

2

Fig. 1 is a perspective view of a microphone constructed in accordance with the invention in condition to receive a coating of insulation.

Fig. 2 is a view of a finished microphone shown partly in cross section to illustrate the layers of insulation.

As illustrated in Fig. 1, the microphone includes a holder 1 which has two halves 3 and 5 constructed of a Bakelite type resin or other suitable solid non-conductor, which, when assembled, forms a substantially rectangular block. The two halves of the holder are held together by a bolt 7.

A crystal bank 9 is held in a transverse opening 11 between the two halves of the holder, the opening being of generally rectangular shape and extending completely across the holder as shown. As illustrated, a 4-ply Rochelle salt crystal bank is used as a piezo-electric transducer, the crystal bank being of such a length as to extend the entire length of the transverse opening whereby two faces of the crystal bank are flush with two opposite faces of the holder, as more clearly shown in Fig. 2.

25 Two leads 13 and 15 are connected with the crystal bank 9 and pass through openings 17 and 19 between the halves of the holder to connect the crystal bank with an electrical cable 21.

The cable 21 is a shielded electrical cable of 30 the usual underwater type having a pair of insulated leads 23 and 25 surrounded by a metallic sheath 27 which in turn is covered by an outer waterproof cover 29. The cable 21 connects the microphone with appropriate amplifiers and recording or listening devices (not shown).

The microphone is given a coating of waterproof insulation by dipping it in a neoprene paint. The cable is prepared for dipping by baring the tip portions 31 of the leads and a portion 33 of 40 the shield 27 to put the microphone and cable in the condition shown in Fig. 1. The microphone is cleaned with benzol, carbon tetrachloride, or an equivalent solvent. Then, the first coat of neoprene paint is applied. The microphone is 45 immersed in a non-aqueous solution of a neoprene paint a distance sufficient to cover the exposed faces of the crystal bank 9, the holder 1, and the insulation on the tip portions 31 of the leads, but not the exposed portion 33 of the shield 27, and then withdrawn. One or more dips may be used to give a sufficiently thick protective and insulating first layer 35 (Fig. 2). A 50 non-aqueous and substantially anhydrous solution is used because small amounts of water affect a Rochelle salt piezo-electric transducer adversely.

When this insulating layer 35 has dried, a shielding layer 37 is applied. The microphone is painted with a silver conducting paint or other suitable shielding material. By this operation, the portion already coated with neoprene is completely covered and the shielding paint is extended to cover the exposed portion 33 of the cable sheath 27 making a complete electrostatic shield about the entire microphone which is integral with the sheath 27 but insulated from the crystal bank 9 by the neoprene layer 35 previously applied.

When the shielding layer 37 has dried, the microphone is again dipped in neoprene paint. For this second dip, the microphone is immersed to a sufficient depth to cover all the microphone which was covered with the conducting paint and also to cover part of the waterproof cover 29 of the cable 21 to give an outer waterproof covering 39 completely surrounding the microphone which is integral with the outer cover of the cable. The covering is allowed to dry and cure for several days. If required, two or more layers may be applied. When the outer covering has cured sufficiently, it is dusted with powdered talc to eliminate tackiness and is ready for use.

The completed microphone is shown in Fig. 2. Surrounding the holder 1 and the crystal bank 9 are three layers, the layer of insulation 35, the electrical shielding layer 37 and the outer waterproof covering 39 all bonded tightly together and to the unrestrained faces of the crystal bank 9. There is a continuous solid connection between the crystal bank 9 and the outer protective waterproof covering 39 unbroken by air spaces, and the layers act as a diaphragm conducting sound vibrations to the crystal bank with little loss in intensity.

This microphone has excellent electrical response. Experiments with microphones constructed in accordance with this invention have shown them to be relatively non-directional in character. The direct bonding of the waterproof covering to the crystal bank transducer makes the microphone more sensitive than other types of underwater microphones. Moreover, the waterproof neoprene covering gives a tough outer covering about the microphone which protects the crystal bank from ordinary shocks.

This microphone withstands higher static pressures than other known instruments. It has been tested under fluid pressures up to 600 lbs. per square inch. In conventional types failure is caused at such pressures by collapse of the diaphragm or breaking of the fluid seal. In this instrument, due to the intimate bonding of the neoprene coating to the transducer, there is a fluid seal provided without the use of a mechanical diaphragm and the microphone is therefore more rugged than those of other types.

This microphone has been found to be of particular value in underwater sound reception and measurement, but may be used satisfactorily for other purposes as well.

Having described our invention what we claim as novel and desire to protect by Letters Patent of the United States is:

1. A microphone comprising a transducer, a holder for said transducer, a cable connected to said transducer, said cable having an electrostatic shielding sheath and an outer waterproof cover, a layer of thin, flexible, waterproof insulation surrounding said transducer and said holder, a layer of thin, flexible, electrostatic shielding material surrounding said insulation

and engaging said sheath, and a second layer of thin, flexible, insulation surrounding said shielding material and engaging said outer waterproof cover, said layers of insulation being bonded to said layer of shielding material, said first-mentioned layer of insulation being bonded to said transducer, the composite coating of said layers of insulation and shielding material thereby being adapted to vibrate integrally with said transducer.

2. A hydrophone comprising a piezoelectric crystal, holding means for said crystal comprising a substantially rectangular block of insulating material having an opening therethrough conforming to the size and shape of said crystal, said holding means being arranged to expose two vibratory faces of said crystal, a two-conductor cable having an electrostatic shield and an outer waterproof sheath electrically connected to said crystal, a layer of flexible, insulating material enclosing said crystal and said holding means, said layer of insulation being bonded to said exposed faces of said crystal and to said outer sheath of said cable, and a flexible electrostatic shield imbedded in said layer to completely surround said crystal and said holding means and engaging the electrostatic shield of said cable.

3. A hydrophone comprising, in combination, a piezoelectric transducer, a holder of insulating material firmly contacting said transducer to expose two faces thereof, a two conductor cable having its two conductors individually insulated, a metal sheath enclosing both said conductors and an outer insulating sheath surrounding said metal sheath, said two conductors having the insulation removed from a short length on an end thereof and extending into said holder for electrical connection with said transducer, and said metal sheath and said outer sheath being removed from successively slightly longer lengths, respectively, from said end of said cable, a first, thin, flexible layer of waterproof insulating material completely covering said holder and transducer and the exposed insulation of the individual conductors of said cable and being adhesively bonded thereto, a thin, flexible layer of conducting material completely surrounding said first layer and circumferentially contacting said metal sheath of said cable, and a second, thin, flexible layer of waterproof insulating material completely surrounding said layer of conducting material and the end region of the outer insulating sheath of said cable, said first and second layers of insulation and said conducting layer being adhesively bonded to each other whereby the composite coating is adapted to vibrate integrally with said transducer.

4. A hydrophone comprising, a piezoelectric crystal, means for holding said crystal to expose two vibratory faces thereof, a cable having an electrostatic shielding sheath and an outer waterproof cover connected to said crystal, a first layer of waterproof insulation surrounding said crystal and said holding means and bonded to the exposed faces of said crystal, a thin flexible layer of shielding material surrounding said first layer of insulation and engaging the sheath of said cable, and a second layer of waterproof insulation surrounding said shielding material and bonded thereto and engaging the outer cover of said cable, the composite coating of said layers forming a diaphragm adapted to vibrate integrally with said crystal.

5. A microphone comprising, a piezoelectric

crystal, a holder for said crystal, a cable having an electrostatic shielding sheath and an outer waterproof cover connected to said crystal, a first thin layer of flexible waterproof insulation surrounding said crystal and said holder, a thin layer of flexible electrostatic shielding material surrounding said first layer of insulation and engaging said sheath, and a second thin layer of flexible insulation surrounding said shielding material and engaging the outer cover of said cable, said first layer of insulation being bonded to said crystal and holder and to said electrostatic shielding material, said second layer also being bonded to said electrostatic shielding material, the composite coating of said layers of insulation and shielding material thereby being adapted to vibrate integrally with said crystal.

6. A hydrophone comprising a bank of piezoelectric crystals, a holder for said crystals comprising a split-block of insulating material of generally rectangular shape having an opening therethrough shaped to firmly hold said bank of crystals to expose two vibratory faces thereof, a two conductor cable having an electrostatic shield and a waterproof outer cover, the conductors of said cable being positioned between two crystals of said bank and maintained in firm electrical contact therewith by said holder, a first thin layer of flexible waterproof insulation completely covering said crystals and said holder and being bonded thereto, a thin, flexible layer of conducting material surrounding said first layer and engaging the electrostatic shield of said cable, and a second thin layer of flexible waterproof insulation surrounding said layer of conducting material and engaging the outer cover of said cable, said layers being adhesively bonded to each other whereby the composite coating is adapted to vibrate integrally with the vibratory faces of said crystals.

20

25

40

7. A hydrophone comprising a piezoelectric crystal, a holder of insulating material firmly contacting said crystal to expose two vibratory faces thereof, a two conductor cable having an electrostatic shielding sheath and an outer waterproof cover, said conductors being bared of their insulation at one end and firmly held in contact with said crystal by said holder, a first thin layer of neoprene completely covering said crystal and said holder and engaging the insulation on said two conductors, a thin flexible layer of metal completely surrounding said first layer of neoprene and engaging the electrostatic shield of said cable, and a second thin layer of neoprene completely surrounding said layer of metal and engaging the outer cover of said cable, said layers being bonded together whereby the composite coating is adapted to vibrate integrally with the vibratory faces of said crystal.
